UNITED STATES PATENT OFFICE.

CHARLES C. BREAKFIELD, OF ALLENSTVILLE, KENTUCKY, ASSIGNOR OF ONE-HALF TO
JESSE B. BOYD, OF ALLENSTVILLE, KENTUCKY.

ATTACHING PLATE FOR SPRINGS.

Application filed January 4, 1924. Serial No. 684,388.

To all whom it may concern:

Be it known that I, CHARLES C. BREAKFIELD, a citizen of the United States, and a resident of Allensville, in the county of Todd and State of Kentucky, have invented certain new and useful Improvements in Attaching Plates for Springs, of which the following is a specification.

This invention relates to attaching plates especially adapted for use in connection with the front springs of "Ford" automobiles.

Briefly stated, an important object is to provide an attaching plate adapted to be positioned below the semi-elliptical spring on the front of an automobile so as to brace the intermediate portion of the spring and thereby prevent the same from breaking in the vicinity of the bolt receiving holes therein.

20 A further object is to provide an attaching plate having means to force the intermediate portion of the semi-elliptical spring well up into the channeled cross member so that the spring and the channeled cross member are securely and positively connected whereby the possibility of breakage is reduced to a minimum.

Another important aim of the invention is to provide an attaching plate of the character specified adapted to positively hold the spring against excessive lateral movement with relation to the cross member so that the strain on the spring perches and associated elements is reduced to a minimum.

35 A further object is to provide an attaching plate which may be applied without elaborately altering the construction of the vehicle and without the exercise of unusual skill.

40 A further object is to provide an attaching plate of the character specified which is of highly specified construction, durable in use and cheap to manufacture.

Other objects and advantages will be apparent during the course of the following description.

In the accompanying drawing forming a part of this application, and in which like numerals are employed to designate like parts throughout the same:

Figure 1 is a side elevation of the improved attaching plate applied;

Figure 2 is a bottom plan view of the plate applied to the spring and the channeled cross member;

Figure 3 is a vertical transverse sectional view, taken on line 3—3 of Figure 1;

Figure 4 is a vertical transverse sectional view, taken on line 4—4 of Figure 1; and

Figure 5 is a perspective of the improved attaching plate.

In the drawing wherein for the purpose of illustration is shown a preferred embodiment of the invention, the numeral 5 designates a longitudinally curved channeled cross member forming a part of the standard construction of a "Ford" automobile and connected at its ends to the side members of the vehicle frame.

Figure 1 illustrates that the semi-elliptical cross spring 6 is partially received in the channeled cross member 5 and is connected at its ends to perches 7, all of which is old and well known.

The improved attaching and strengthening plate is designated generally by the numeral 10 and is secured beneath the spring 6 by means of U-shaped hangers or bolts 11 having nuts 12 to secure the plate in place. Figure 1 illustrates that the bolts 11 are extended through laterally projecting ears 14 at the ends of the plate, and the upper side of the plate is provided with a longitudinally extending raised portion or shoulder 16 capable of being received in the channeled cross member 5. Therefore, when the nuts 12 are tightened the raised portion 16 forces the intermediate portion of the spring 6 well up into the channeled cross member 5. This provides an extremely rigid connection between the spring 6 and the cross member 5 and also takes up slack.

The connection between the cross member 5 and the spring 6 is further strengthened by means of a U-bolt 20, the back portion of which is spread to form a support for a bearing 22 which receives the hand crank. The terminal portions of the bolt 20 are provided with nuts 25 extending through certain of the ears 14.

With reference to the foregoing description taken in connection with the accompanying drawing it will be seen that the elongated plate 10 and the fastening devices therefor effectively protect the spring, the cross member and the perches from breakage. Attention is especially directed to the fact that the invention forming the subject-matter of this application prevents the spring from rocking and the strain on the

perches 7 is thereby reduced to a minimum and the wear on these parts is also limited.

The presence of the shoulder or raised portion 16 add greatly to the value of the plate since it enables the spring to be held well within the cross member 5 and this prevents rattling and looseness at this point.

It might be stated that the principal strain on the spring is transmitted to the intermediate portion of the spring and this portion is provided with aligned apertures for the reception of the fastening bolt 30 by means of which the several leaves are connected. Figure 4 illustrates that a nut 31 is threaded on the bolt 30 and is received in an opening 33 in the attaching plate. This major strain on the spring at the weakened central portion of the same is successfully met by the elongated plate which extends a substantial distance beyond the apertures in the several leaves.

The invention forming the subject-matter of this application prevents both the cross member 5 and the spring 6 from breakage and the improved plate may be quickly and conveniently applied without elaborately altering the construction of the vehicle.

Also the attaching plate is capable of use in connection with buggy springs and other vehicle springs although it is especially adapted for use in the manner illustrated.

It will be seen that the attaching plate forming the subject of this application prevents excessive rocking of the vehicle and prevents the fenders from coming in contact with the tires and rapidly wearing the tires and also getting the fenders out of shape.

Also the invention forming the subject matter of this application maintains the curvature of the spring and prevents the same from straightening out and settling. By thus preserving the arch of the spring the flexibility of the same is also preserved and the body is prevented from settling.

Having thus described the invention, what is claimed is:

The combination with a channeled cross member of an automobile frame, of an attaching member for securing a leaf spring thereto, comprising a body having its upper side provided with a raised portion extended for the full length thereof and adapted to be freely received in the channeled cross member and having a convex upper surface for flatly contacting with the intermediate portion of the original leaf spring of the automobile, said body being provided at a point spaced below the lower edge of the channeled cross member with spaced laterally projecting ears at the intermediate and end portions of the body and extending beyond the outer sides of the channeled cross member, and fastening devices extending through said ears at the intermediate and end portions of the body for firmly holding the raised portion of the body in the channeled cross member, the convex upper surface of the body extending for the full length of the body and being entirely unbroken except for a single centrally located opening extending through the body and opening out through the upper surface of the raised portion.

CHARLES C. BREAKFIELD.
